[57] **ABSTRACT**

An internal combustion reciprocating engine having a highly transparent window replacing the head or a portion thereof provides a modulated infrared radiation source whereby the radiation from the combustion gases passing through the window is essentially fully modulated at varying frequencies.

FIG. 3

FIG. 4

HIGH INTENSITY MODULATED INFRARED RADIATION SOURCE

BACKGROUND OF THE INVENTION

Prior to the present invention the primary sources of infrared radiation have been the electrically powered or combustion heated blackbody and the arc lamp. The primary drawback with such devices has been their inefficient use of relatively high levels of electrical input power for the electrical sources and the relatively complex materials and assembly procedures required for the combustion heated sources.

To provide complex modulation of the arc lamp output requires modulator electronics of undue complexity. Modulation of blackbody sources has generally been provided through the use of rotating choppers or vanes which while satisfactory are relatively complex and costly, inefficient, or much larger than the basic source itself.

SUMMARY OF THE INVENTION

Accordingly, it is an object of this invention to provide a new and novel modulated source of infrared energy.

It is another object of this invention to provide a high temperature source of infrared radiation which is essentially fully modulated at varying frequencies.

It is a further object of this invention to provide a modulated infrared source having no additional modulators.

Briefly, a high intensity modulated infrared source is provided by replacing the head or portions thereof of an internal combustion reciprocating engine with a window having high transmissibility in the infrared spectrum.

BRIEF DESCRIPTION OF THE DRAWINGS

The above-mentioned and other features and objects of this invention will become more apparent by reference to the following description, taken in conjunction with the accompanying drawings, in which:

FIG. 1 is a sketch of the top view of a high intensity modulated infrared source in accordance with the present invention;

FIG. 2 is a sketch in section of the source of FIG. 1;

FIG. 3 is a sketch of the output waveform from a one cylinder engine; and

FIG. 4 is a schematic of the modulator of FIG. 1 having speed control.

DESCRIPTION OF PREFERRED EMBODIMENTS

Referring now to FIGS. 1 and 2, there is illustrated simplified diagrams of a basic high intensity modulated infrared source in accordance with the present invention. The source comprises an internal combustion reciprocating engine 10 of conventional form (only a portion of which is shown for clarity) having at least one cylinder 12 with an associated piston 14, intake and exhaust valves 16 and 18, and a spark plug 20. It should be noted that spark plug 20 is displaced from its conventional position at the centerline of cylinder 12 so as not to block any radiation emitted from the device, as will be described hereinafter. Of course for diesel engines no spark plug is required.

The head or a portion thereof of engine 10 is removed and a window 22 is placed over cylinder 12 held by, for example, brackets 24 and 26. Window 22 serves two functions; it contains the combustion gases and allows transmission of the radiation in the spectral region of interest. Preferably window 22 is constructed of sapphire or polycrystalline alumina. Quartz can be used; however, it lacks the strength and the desired 3-5 micron transmissibility of the other two materials.

A dish may be arranged about the window 22 to appropriately shape the pattern of radiation exiting therefrom.

The post-combustion gaseous mixture existing in an internal combustion engine approximates a 2,700° K radiator with a high emissivity in the 1-5 micron region, and essentially 1 in the region of rotational or vibration bands of any of the molecular species present (CO₂, N₂, H₂O). The radiation is essentially modulated at 100 percent levels, since the gases are cooled substantially as the piston 14 retreats into the cylinder 12. The temperature of the gases cools to essentially the temperature of the cylinder walls of about 150° C at the completion of the intake stroke. Thus, modulation is achieved inherently without the provision of additional equipment.

FIG. 3 is a sketch of the radiation pulse train exiting the window 22 and it is seen that essentially full modulation is achieved. The radiation pattern can be varied in pulse shape, frequency and duty cycle. To vary the pulse shape of the radiation the timing is altered by either advancing or retarding the spark from plug 20 in the conventional manner. The frequency of the signal is altered by opening and closing the throttle (not shown). For accurate speed control, a load, such as an electrical generator, can be applied to the engine. Mechanical means such as a Prony brake also can be used. However, the latter means is difficult to regulate and the dc generator load is preferred. Without a load the air-fuel mixture intake is throttled, thereby providing temperatures and pressures within the cylinder less than required for optimum operation.

FIG. 4 illustrates schematically a preferred system wherein the output from a motor 30 taken at a crank shaft 32 is mechanically coupled to a dc generator 34. An ac generator could also be used. Accurate speed and, thus, frequency control is achieved by setting the dc voltage control 36 of the generator 34 and by varying the power thereof through a load resistor control 38. Preferably, the throttle to the engine is maintained wide open to supply as much combustion to the cylinders with the load being used as the limiting means. Generator 34 may be used to supply electrical power to an overall system by, for example, charging a battery.

When more than one cylinder is used, the duty cycle of the radiation is changed.

Optimum infrared radiation occurs in the region near five microns.

Although the invention has been described in conjunction with a four cycle internal combustion reciprocating engine, two cycle engines, diesel engines and rotating engines may be used. Thus, it is to be clearly understood that the description is made only by way of example, and not as a limitation of the scope of my invention as set forth in the accompanying claims.

I claim:

1. A new use for an internal combustion engine having a window with good transmissibility in the infrared as a high intensity modulated infrared radiation source, comprising the steps of:

generating combustion gases within the internal combustion engine; and
passing modulated infrared energy through the window of the engine while blocking substantially all of the visible energy from passing through the window.

2. The new use for an internal combustion engine as recited in claim 1,
further including the step of altering the modulated infrared energy passing through the window.

3. The new use for an internal combustion engine as recited in claim 1, further including the step of shaping the pattern of radiation passing through the window.

4. A high intensity modulated infrared radiation source, comprising;

an internal combustion engine having at least a portion of the head removed thereby providing an

opening to at least one cylinder thereof;
a window enclosing the opening, said window having a high transmissibility in the infrared such that essentially fully modulated infrared radiation is obtained from the combustion gases during operation; and

5 a reflector arrayed about said window for shaping the pattern of radiation exiting said window.

10 5. A high intensity modulated infrared radiation source, comprising;

an internal combustion engine having at least a portion of the head removed thereby providing at least one opening to at least two cylinders thereof; and

15 at least one window enclosing said opening, said window having a high transmissibility in the infrared such that essentially fully modulated infrared radiation is obtained from the combustion gases during operation.
